CLAIM

The ornamental design for a combined telephone housing and handset therefor, substantially as shown and described.

DESCRIPTION

FIG. 1 is a front elevation of a combined telephone housing and handset therefor, showing my new design;

FIG. 2 is a left side elevation thereof;

FIG. 3 is a right side elevation thereof;

FIG. 4 is a top plan view thereof;

FIG. 5 is a rear elevation thereof;

FIG. 6 is a bottom plan view thereof; and

FIG. 7 is a front elevation with the handset removed from the telephone base for clarity of illustration.

FIG. 3

FIG. 1

FIG. 2

FIG. 5

FIG. 6
